TYPEWRITING MACHINE

Richard V. Reppert, Binghamton, N. Y., assignor
to International Business Machines Corpora-
tion, New York, N. Y., a corporation of New
York

Original application December 18, 1933, Serial
No. 702,856. Divided and this application Sep-
tember 26, 1934, Serial No. 745,542

4 Claims. (Cl. 197—17)

The present invention relates to power oper-
ated typewriting machines and is a division of
my copending application Serial No. 702,856 filed
December 18, 1933.

5 The broad object of the invention is to provide
a simple and effective device for controlling the
impact force of the type bars or other printing
instrumentalities whereby a typewriting machine
may be readily adjusted to the quality or thick-
10 ness of the paper or the number of typewritten
copies desired.

Another object is to provide an impact con-
trolling device which is easily incorporated in
machines now in use.

15 Various other objects, advantages, and fea-
tures of the invention will be pointed out in the
following description and claims or will be ap-
parent from a study of the drawing which rep-
resents a vertical section of a power operated
20 typewriter.

While this invention has been illustrated in
the drawing in connection with the power type
bar action disclosed in my copending application
above mentioned, the present invention is capable
25 of being used in other typewriting machines now
on the market or already in use. As the specific
construction of the power type bar action is not
of particular importance, so far as an understand-
ing of the present invention is concerned, only a
30 brief general description of its operation will be
given herein.

In manually operated typewriting machines,
the force of impact is easily regulated by the
operator who learns by experience the proper
35 amount of pressure or speed of the fingers in
striking on the keys. When single sheets are
being typed, a light pressure or blow is preferable
and sufficient to produce clear imprints without
cutting the paper. When a number of carbon
40 copies are desired, the operator increases the
force applied to the keys in proportion to the
number of copies required.

The situation is different in modern high speed
power operated typewriting machines as the keys
45 merely operate or release mechanisms which
subsequently connect the type bars or other print-
ing instrumentalities to a power driver or uni-
versal actuator of some sort. The pressure re-
quired to operate the keys and the amount that
50 they may be depressed is constant regardless of
the nature of the work to be done and it is im-
material how hard or how fast the keys are
struck.

The practice in the art varies in respect to
55 how the force of the blow is regulated. In some

machines the force of the blow may be varied
by changing the duration of time the type bars
are connected to the power operator so that they
may remain under control of the power operator
for a longer period when one or more carbon
5 copies are desired than when writing on a single
sheet. As the number of carbon copies desired
is increased, the machine may be adjusted so
that the type bars are connected to the power
operator for progressively longer periods. In
10 other machines the same results are obtained by
increasing the speed of the power operator in
accordance with the number of copies desired,
as by cutting out resistance in series with the
driving motor. Both of these methods are used
15 in commercial machines.

The first method is objectionable as it requires
a very careful adjustment of the machine and
the parts necessary for its accomplishment are
subject to wear and also because the degree of
20 adjustment is extremely limited by such prac-
tical considerations as the size and proportions
of the parts of the power system.

The second method is objectionable as, while it
is the simplest of all, it requires that the machine
25 be increased in speed beyond normal require-
ments in producing carbon copies thereby intro-
ducing wear problems and narrowing the time
allowed for proper response of the parts to the
limit of safety for reliable operation.

30 The present invention aims to provide a method
which is intermediate the two methods in the
senses of requiring fewer parts than the first
method and having the simplicity of the second
method, while retaining the beneficial features
35 of both. The problem of wear on the power
driver and connected parts will be eliminated so
far as any effect upon the regulating of the force
of the blow is concerned, the amount of wear
being no greater than would be the case if no
40 impact controlling mechanism were provided.

A convenient method of regulating the force
of the blow without providing many additional
parts subject to wear or derangement consists
in taking advantage of the energy absorbing
45 properties of the usual spring actuated universal
bar directly actuated by the type bars and com-
monly used in commercial machines like the
"Underwood", for example.

In the drawing there is shown a pivoted type
50 bar 1 mounted and operated by a sub-lever 2
in a manner now commonly employed in many
commercial machines such as the Underwood.
The specific means for operating type bar 1 is
immaterial but for convenience it has been shown

30

45

55

in connection with a power type bar action like that disclosed in copending application Serial No. 702,856. In this mechanism, the depression of a key 4 causes a detent 5 carried by the key lever 5 to move to the left, thereby permitting a spring 6 to rock an element 7 counterclockwise.

A toothed disk or star wheel 8 rotatably mounted on element 6 is thus caused to positively engage the teeth of a constantly rotating power actuator 9 which may be driven by a motor in the usual way.

The disk 8 is rotated by the actuator 9 and its initial rotation causes element 6 to be relatched by detent 5 while its subsequent rotation causes 15 sub-lever 2 to be rocked clockwise by a cam finger 10 secured to said lever and in the path of the teeth in disk 8. Clockwise movement of the sub-lever 2 causes the type bar to move in an arc until it strikes the platen 11. A spring 12 connected to sub-lever 2 restores the type bar and sub-lever after each operation. The proportions 20 of the parts and their relative positions are such that at a reasonably low speed of the power operator 9 there will be sufficient impact force of 25 the type bars to take care of the heaviest work which the machine may be required to perform. Preferably the parts of the power drive mechanism, notably cam finger 10 and disk 8 are so related that no driving force is imparted to 30 the type bar by actuator 9 beyond the point where the type bar operatively engages the universal bar hereinafter to be described. This condition is not essential but is preferred as with it the load on the power actuator will be nearly always constant, at least as far as the operation of the type 35 bars is concerned, regardless of the adjustment of the impact controlling device. In some cases, particularly machines designed for extra heavy duty as where a very large number of carbon 40 copies is desired, it may be necessary to keep the type bar under the influence of the power actuator for a longer period in order that the maximum force of impact may be as great as possible.

Each type bar 1 has a shoulder or "heel" 13 45 which is adapted, when the type bar is near the platen 11, to strike a universal bar 14. The latter is of a form commonly used in the art, it being found in "Underwood" machines, for instance, and ordinarily controls the carriage escapement 50 or letter spacing mechanism. When struck by the heel 13 of a type bar, the universal bar moves a small amount rearwardly of the machine (to the left in the drawing) against the tension of a spring 15. Normally the spring 15 exerts only 55 slightly more tension on the universal bar 14 than is necessary to assure restoration of the universal bar when the type bar is restored by spring 12 to provide a fair margin of safety. It is evident that the resistance offered by universal bar 14 to the 60 movement of the type bars will normally be fairly constant in value with a given size of spring and a fixed point of connection of the spring to the frame of the machine.

Means is provided, according to the present invention, for varying the tension of the spring 15 in order that the amount of energy absorbed by the spring may be varied thereby controlling the force of impact of the type bar. Spring 15 instead of being fixedly mounted in the usual way, 70 is anchored to the free end of an arm 16 secured to a shaft 17. The latter is journaled in the framework of the machine and extends toward the right hand side plate of the machine. Adjacent the right hand side frame there is secured to 75 shaft 17 a worm sector 18 with which cooperates

a worm 19 secured to a shaft 20 journaled in the framework. The shaft 20 extends through the front plate of the machine conveniently near the keyboard and secured to this shaft is a knob or finger piece 21 having a suitable index or pointer 5 22. The latter cooperates with a suitable scale on a plate 23 secured to the front plate or the scale may be placed directly on the front plate.

By rotating knob 21 by hand, the operator of the machine can increase or decrease the tension 10 of spring 15 thereby decreasing or increasing the force of impact of the type bars.

Obviously, as the tension of spring 15 increases the resistance offered by the universal bar 14 to the movement of the type bars as they approach 15 the platen will increase and the force of impact will be decreased thus weakening the impressions produced by the type bars. When the universal bar is used to operate the escapement mechanism and/or the ribbon vibrator as is usually the case, 20 the spring 15 must always have a certain amount of tension and in such cases it will be desirable to provide suitable limit stops to prevent the knob 21 from being set to place spring 15 under less tension than necessary for proper operation of 25 the escapement mechanism and/or ribbon vibrator and to prevent placing spring 15 under too great a tension. In machines having a separate universal bar for operating the ribbon vibrator and/or escapement mechanism, the construction 30 shown in the drawing may be employed but a single stop will probably suffice to prevent turning the knob 21 far enough to cause either compression of spring 15 or stretching thereof sufficient 35 to produce permanent deformation of the springs. These stops have not been shown as they are purely a matter of judgment and skill in construction.

One of the important features of the construction shown in the drawing is its simplicity which 40 requires very few parts. Another feature of importance is the fact that the invention may be readily applied to existing power driven typewriting machines not equipped with impact controlling means as by very slight changes in the 45 design of the parts the mechanism herein described can be easily manufactured as an attachment since most power driven typewriters have a universal bar like 14 for operating either the escapement mechanism or ribbon vibrator or both.

Other very important features of the construction are the facts that it need not impose any additional load on the power drive mechanism or interfere with the proper operation of 55 the power drive mechanism or cause wear therein.

The present invention has been illustrated and described as embodied in a specific form in connection with a specific type of power type bar action; however it is limited neither to the form 60 nor type of power type bar action shown as the invention may take other forms, or be modified in detail, or be used in connection with other forms of power type bar action. Accordingly it is desired that the following claims be limited in 65 scope only by the prior art.

What is claimed is:

1. In combination, a type bar, power means 70 for operating the type bar, a universal bar actuated by the movement of the type bar, a spring acting on said universal bar in a direction to cause the universal bar to retard movement of the type bar and reduce its velocity, and a manually adjustable tension regulating device connected to the spring and operable at will to reg- 75

ulate the tension of the spring whereby to control the velocity of the type bar, said device comprising a pivoted arm to which the spring is connected, a shaft having a finger piece for turning the shaft and a pointer cooperating with a fixed scale, and a worm and sector connection between the arm and shaft.

5. 2. In combination, a platen adapted to support a record sheet, a printing member movable toward the platen to effect an impression, power means for moving said member, means for retarding the movement of the member toward the platen including a spring, and a manually adjustable tension regulating device connected to the spring and operable at will to regulate the tension of the spring whereby to regulate the impact pressure of the printing member on the record sheet, said device comprising a rotatable arm to which the spring is connected, a rotatable finger piece, and a worm and sector driving connection between said finger piece and arm.

10. 3. In combination, a platen adapted to support a record sheet, a printing member movable toward the platen to effect an impression, power means for moving said member, means for retarding the movement of the member toward

the platen including a spring, and a manually adjustable tension regulating device connected to the spring and operable at will to regulate the tension of the spring whereby to regulate the impact pressure of the printing member on the record sheet, said device comprising a rotatable finger piece, and worm and sector means connecting said finger piece and spring whereby rotation of the finger piece changes the tension of the spring.

5

15. 4. In combination, a platen adapted to support a record sheet, a printing member movable toward the platen to effect an impression, power means for moving said member, means for retarding the movement of the member toward the platen including a spring, and a manually adjustable tension regulating device connected to the spring and operable at will to regulate the tension of the spring whereby to regulate the impact pressure of the printing member on the record sheet, said device comprising a rotatable finger piece, a worm actuated by said finger piece, and a member having a toothed relation to the worm and connected to said spring whereby rotation of the worm by said finger piece varies 20 the tension of said spring.
